Des. 193,173
Patented July 10, 1962

193,173

VACUUM CLEANER RUG TOOL

Theodore G. Daher, Stratford, Conn., assignor to General Electric Company, a corporation of New York

Filed June 12, 1961, Ser. No. 65,555

Term of patent 14 years

(Cl. D9—2)

Fig. 2.

Fig. 3

Des. 193,173

PAGE 4

Fig. 4.

FIG. 1 is a front perspective view of a vacuum cleaner rug tool embodying my new design;

FIG. 2 is a front elevational view thereof;

FIG. 3 is a top plan view thereof;

FIG. 4 is a side elevational view thereof;

FIG. 5 is a rear perspective view thereof.

The dominant features of the design reside in the portions shown in full lines.

I claim:

The ornamental design for a vacuum cleaner rug tool, substantially as shown and described.
